UNITED STATES PATENT OFFICE.

JOHN H. WITZEL, OF NEW YORK, N. Y., ASSIGNOR TO BIGELOW CARPET COMPANY, A CORPORATION OF MASSACHUSETTS.

DESIGN FOR A RUG.

40,633.

Specification for Design.

Patented Apr. 12, 1910.

Application filed February 21, 1910. Serial No. 545,256. Term of patent 7 years.

To all whom it may concern:

Be it known that I, JOHN H. WITZEL, a citizen of the United States, residing at the city of New York, State of New York, have invented a new, original, and ornamental Design for Rugs, of which the following is a specification, reference being had to the accompanying drawing, forming part thereof.

The figure is a plan view of one of the like quarters of a rug, showing my new design.

I claim:

The ornamental design for a rug, as shown.

JOHN H. WITZEL.
